UNITED STATES PATENT OFFICE

HARRY M. PFLAGER, OF ST. LOUIS, MISSOURI, ASSIGNOR, BY MESNE ASSIGNMENTS, TO GENERAL STEEL CASTINGS CORPORATION, OF GRANITE CITY, ILLINOIS, A CORPORATION OF DELAWARE

BOOSTER-MOTOR SUPPORT

Application filed January 16, 1928. Serial No. 247,154.

My invention relates to railway rolling stock and consists in a novel support for a booster motor.

The term, booster motor, as will be readily understood by those skilled in the art, is applied to a motor operatively connected to a normally non-driving axle and intended to be used under abnormal conditions such as when the locomotive is starting or is laboring up a steep grade. The motor projects horizontally from the axle to which it is attached and the projecting portion of the motor is supported on a truck or from the main frame work of the locomotive. This support has previously taken the form of a spherical bearing beneath the longitudinal center line of the locomotive, which bearing has permitted the motor to tilt and turn relative to the truck or frame work according to the movements of the axle to which it is attached.

The main object of my invention is to provide a booster motor support which may be applied to the motor at the sides thereof and, preferably, may support the motor throughout its width and, at the same time, permit the motor to move with the axle to which it is attached.

An additional object of my invention is to equalize the weight of the motor, when the latter is supported as described, so that the supporting structure will not have the load concentrated at one side under any condition. Preferably, I desire to support the motor from the longitudinal center line of the locomotive structure.

The above and other more detailed objects of my invention are attained by the structure illustrated in the accompanying drawings forming a part of this application and in which:

Figure 1 is a top view of one longitudinal half of the rear end of a locomotive frame work with a radial trailer truck applied thereto and including a booster motor.

Figure 2 is a side elevation of the same structure.

Figure 3 is a vertical transverse section through one-half of the structure taken substantially on the line 3—3 of Figure 2.

Figure 4 is a similar section illustrating a modified structure.

Figure 5 is a detail vertical section taken on line 5—5 of Figure 4.

Figures 6 and 7 are views corresponding to Figures 1 and 2 but illustrating a modification in which the rearward extension of the main frame of the locomotive forms a non-radial truck having pedestals for guiding journal boxes in which the trailer axle is journaled.

Figure 8 is a vertical transverse section taken substantially on the line 8—8 of Figure 7.

Figure 9 is a section similar to Figure 8 but illustrating a modified structure.

In the drawings illustrating the preferred embodiment of my invention, the main frame of the locomotive is indicated at 1 and is shown as provided with a rearward extension or cradle 2 which carries the fire box, ash pan, and cab of the locomotive, which parts are not illustrated as they form no part of my present invention. The rear driver of the locomotive is indicated at 3. A trailer truck frame is pivoted to the locomotive at 5 and is mounted upon a pair of non-driving wheels 6 which support the frame through their axle journals 7, springs 8, hangers 9, and an equalizer 10. The rear ends of the wheel pieces 4 of the truck frame are connected by a cross rail 11.

A booster is indicated at B and is operatively connected to the truck axle 12 and is partially supported on the latter by means of bearings 13. The rear portion of the motor B projects over the transverse member 11 of the truck frame and is carried on the transverse beam 14 which preferably is rigidly attached to the motor and supports the same from side to side or which, if desired, may form an integral part of the motor frame. This beam 14 is supported at its outer ends by suitable links 15 which in turn are suspended from a transverse equalizer 16 pivoted at 17 to the locomotive main frame extension element 2.

The pivotal connection 17 for equalizer 16 permits the latter to swing in a vertical plane and the pivotal connections between equalizer 100

16 and links 15 and between the latter and beam 14 permits the links and the beam to swing transversely and longitudinally of the locomotive. This enables the booster to shift 5 with the axle 12 irrespective of any corresponding movement of the main framing of the locomotive.

A different pivotal connection between the booster carrying beam and the main frame is indicated in Figures 4 and 5 in which the pivots 18, 19, and 20 have parallel axes to freely accommodate movement of equalizer 21, links 22 and beam 23 in a plane extending transversely of the locomotive.

15 In the modification illustrated in Figures 6, 7, and 8, the locomotive cradle 24 also forms a rigid or nonradial truck in which is journaled the axle 25 mounted on the non-driving wheels 26. This axle is adapted to be driven 20 by the booster motor M, which is supported from the rear portion of cradle 24 through a cross equalizer 27 pivoted on the cradle at 28 and pivotally suspending the links 29 which 25 pivotally support the opposite end of a beam 30, carrying the booster motor.

A similar general arrangement with a different link pivot is illustrated in Figure 9 in which the links 30 are pinned to the equalizer 31 and to the cross beam 32, similar to the arrangement shown in Figures 4 and 5.

30 In each of the structures shown, the main frame element or cradle is provided with a central bracket located approximately on the longitudinal center line of the locomotive and 35 forming the bearing for the equalizer pivot pin.

In each of the cross sections I illustrate the booster housing H without detailing the motor structure and it will be understood that 40 any effective motor construction may be contained in the housing or mounted upon the motor bed plate P.

With my invention the motor may be carried by supports located at the sides of the 45 motor and the motor may be supported substantially throughout its width. At the same time, the weight of the motor is applied to the framing of the locomotive at a central point on the latter. If the frame tilts transversely, 50 there will be less movement of the support element, relative to the trailer axle, than if the support element was mounted on the sides of the frame. This also avoids a plurality of 55 connections to the sides of the locomotive framing and permits free movement of the motor support to accommodate the trailer axle.

I contemplate the exclusive use of such 60 other variations in the details of construction as come within the scope of my claims.

I claim:

1. In a locomotive, an axle, a booster motor operatively connected to said axle and extending transversely thereof, and a beam en-

gaging and supporting said motor substantially throughout the width of the motor.

2. In a locomotive, a main frame member, a truck pivoted to said member and including an axle, a booster motor operatively connected to said axle, and means suspended from said member at the longitudinal center line thereof and supporting said motor at the sides of the latter and permitting it to move with said axle relatively to said member. 70

3. In a locomotive, a main frame member, a truck pivoted to said member and including an axle, a booster motor operatively connected to said axle, and a beam extending beneath and engaging and supporting said 80 motor substantially throughout the width of the motor and carried by said member so as to permit movement of said motor with said axle.

4. In a locomotive, a main frame member, 85 and an element extending transversely of the locomotive and supported between its ends from said member and adapted to suspend a booster motor from points on either side of its support.

5. In a locomotive, a main frame member, and an element extending transversely of the locomotive and pivotally supported between its ends from said member and suspending a booster motor from points on either side of 90 its support.

6. In a locomotive, a main frame member, and an element extending transversely of the locomotive and supported between its ends from said frame, and a booster motor pivotally suspended from said element at points 100 at either side of the support for the latter.

7. In a locomotive, a main frame member, a transverse equalizer element pivoted between its ends to said member near the longitudinal center line of the latter, links suspended from the ends of said element, and a booster motor supported by said links. 105

8. In a locomotive, a main frame member, a transverse equalizer element pivoted between 110 its ends to said member near the longitudinal center line of the latter, links pivotally suspended from the ends of said element, and a booster motor pivotally connected at its sides to said links.

9. In a locomotive, a main frame member, a transverse equalizer element pivoted between its ends to said member near the longitudinal center line of the latter, a transverse beam supported by said element, and a booster 120 motor carried on said beam substantially throughout the width of the motor.

10. In a locomotive, a main frame member, a transverse equalizer element pivoted between its ends to said member near the longitudinal center line of the latter, a transverse beam pivotally supported by said element and a booster motor rigidly mounted on said beam. 125

11. In a locomotive, a main frame member, 130

- connected to said axle, means supported by said member near the longitudinal center line thereof and supporting said motor at the sides of the latter and permitting pivotal movement of said motor in a vertical plane extending longitudinally of the locomotive. 5
29. In a locomotive, a main frame member, a truck pivoted to said member and including an axle, a booster motor operatively connected to said axle, means supported by said member near the longitudinal center line thereof and supporting said motor at the sides of the latter, said means permitting the motor to swing laterally with said truck. 10
30. In a locomotive, a main frame member, a truck pivoted to said member and including an axle, a booster motor operatively connected to said axle, means supported by said member near the longitudinal center line thereof and supporting said motor at the sides of the latter and permitting pivotal movement of said motor transversely and longitudinally of the locomotive, said means also permitting the motor to swing laterally with said truck. 15
31. In a locomotive, a main frame member, a truck pivoted to said member and including an axle, a booster motor operatively connected to said axle, means supported by said member near the longitudinal center line thereof and supporting said motor at points spaced from the longitudinal center line of the latter and permitting pivotal movement of said motor in a substantially vertical transverse plane relatively to the locomotive. 20
32. In a locomotive, a main frame member, a truck pivoted to said member and including an axle, a booster motor operatively connected to said axle, means supported by said member near the longitudinal center line thereof and supporting said motor at points spaced from the longitudinal center line of the latter and permitting pivotal movement of said motor transversely and longitudinally of the locomotive. 25
33. In a locomotive, a main frame member, a truck pivoted to said member and including an axle, a booster motor operatively connected to said axle, means supported by said member near the longitudinal center line thereof and supporting said motor at points spaced from the longitudinal center line of the latter and permitting pivotal movement of said motor longitudinally of the locomotive. 30
34. In a locomotive, a main frame member, a truck pivoted to said member and including an axle, a booster motor operatively connected to said axle, and means supported by said member near the longitudinal center line thereof and supporting said motor at points spaced from the longitudinal center line of the latter, said means permitting the motor to swing laterally with said truck. 35
35. In a locomotive, a main frame mem- 65
- ber, a truck pivoted to said member and including an axle, a booster motor operatively connected to said axle, means supporting said motor at points spaced from the longitudinal center line of said motor on each side thereof, said means being supported by said member at a single point. 70
36. In a locomotive, a main frame member, a truck pivoted to said member and including an axle, a booster motor operatively connected to said axle, means supporting said motor at points spaced from the longitudinal center line of said motor on each side thereof, said means being supported by said member at a single point near the longitudinal center line of the locomotive. 75
37. In a locomotive, a main frame member, a truck pivoted to said member and including an axle, a booster motor operatively connected to said axle, means connected to said motor at points spaced from the longitudinal center line of said motor on each side thereof for supporting said motor from said member, said means being supported by said member substantially on the longitudinal center line of the locomotive. 80
- In testimony whereof I hereunto affix my signature this 10th day of January, 1928.
